UNITED STATES PATENT OFFICE.

FRANK M. LANDRUM, OF DALLAS, TEXAS.

FAN-OSCILLATING DEVICE.

1,333,925.

Specification of Letters Patent. Patented Mar. 16, 1920.

Application filed December 18, 1918. Serial No. 267,233.

To all whom it may concern:

Be it known that I, FRANK M. LANDRUM, a citizen of the United States, residing at Dallas, in the county of Dallas and State of 5 Texas, have invented certain new and useful Improvements in Fan-Oscillating Devices, of which the following is a specification.

This invention relates to new and useful improvements in oscillating fan devices.

10 In the oscillating fans now in common use the wires supplying current to the motor extend from the base of the fan to the center of the motor and as the base is fixed and the motor oscillates, the wires are sooner or 15 later twisted to the breaking point. Frequently the break occurs near the motor making a repair difficult and often impossible. In gear driven oscillating fans the gears are driven by the motor and often 20 the gears hang with the result that the motor is burnt out.

I have designed and produced an oscillating device obviating the use of gears or deflectors as well as avoiding twisting of the 25 wires and giving a positive oscillation which operates under all conditions.

In carrying out the invention an oscillating platform is provided with a fan table eccentrically pivoted on the platform. A 30 fan is secured on the table. A resilient element is fastened to the table and has its opposite portion attached to a fixed point. The fan causes a reaction by its outwardly directed air current which results in a backward oscillation. The resilient element exerts a certain tension on the table; whereby 35 the table is oscillated in the same direction as the platform and reversed by the limiting operation of the flexible connection.

40 The invention will be more readily understood from a reading of the following specification and by reference to the accompanying drawings, in which an example of the invention is illustrated and wherein:

45 Figure 1 is a view of a device constructed in accordance with this invention, parts being illustrated in side elevation and parts in section.

Fig. 2 is a plan view of the same, and 50 Fig. 3 is a detail of the connection between the table and the resilient element.

In the drawings the numeral 1 designates a base on which a circular platform 2 is centrally pivoted. From the periphery of 55 the platform a radial arm 3 extends and on the outer end of the arm a circular table 4

is centrally pivoted. Both the platform and table may be mounted on ball-bearings if desired.

The table is provided with suitable clamps 60 for rigidly holding the circular or angular base of a fan 6. The table is eccentrically mounted on the platform and the latter need not be circular. The fan is positioned with its blades toward the center of the platform. 65 One side of the table overhangs the platform, while the opposite side projects outward from the arm. In order to balance the platform and compensate for the eccentric load imposed by the fan a counter-balancing 70 weight 7 is diametrically disposed under the platform. A stud 8 from the weight extends up through a radial slot 9 in the platform and receives a wing nut 10. The weight may be thus moved away from or 75 toward the center of the platform to compensate for fans of different weights.

The base 1 is made heavy enough to hold the parts in position and is mounted in a casing 11 which is merged and curved into 80 a vertical column 12 having its front side open. A cap 13 closes the upper end of the column and an adjusting or tensioning screw 14 is threaded therein. The lower end of the screw engages the upper end of an elongated 85 coiled spring 15 which depends through a collar 16 fastened in the column. The column is off-set from the table and the coiled spring is swung in a gradual curve from the collar to the table. The spring has 90 a rectangular eye 17 engaging on an angular stud 18 depending from the table. The eye is fastened on the stud by a nut 19. By this arrangement the table is swung by the lateral displacement of the lower end of the spring. 95 The spring employed is of that type in which the coils contact and is known as a non-compression or extension spring.

It will be seen that when the table is 100 swung or oscillated to the limit of its movement the spring is swung laterally and stretched between the collar and the stud 18, thus causing a reverse movement of the table and platform. As the stud approaches the center of the oscillating movement the 105 tension on the spring is relieved and as the spring cannot be compressed it buckles and swings the table so that the fan is swung over the central line between the collar and the center of the platform. In Fig. 2 the 110 table and fan are in one of the limiting positions or reversing points and the re-

action caused by the revolving of the fan blades will drive the platform and table backward in the direction of the arrows. As the stud 18 reaches the central position 5 of the oscillation the spring is buckled to the point that it throws said stud past the center, thus swinging the table and the fan. The reversing movement is again carried out at the other end of the oscillation.

10 The fan cannot stop with the table on center so that the device will begin to oscillate when the fan is started. The tension of spring can be regulated by adjusting the screw 14 and also the amplitude of the oscillation may be varied by the same adjustment through the length of the portion of the spring which extends below the ring 16. If 15 the length of this portion of the spring is shortened the reversing point will be advanced and the oscillating movement shortened. The electric cord 20 containing the 20

wires supplying current to the fan is supported in a yoke 21 mounted on an arched bracket 22 fastened on the cap 13, so that said cord is free and is not twisted to a 25 breaking point and may be readily removed when the fan is detached from the table.

What I claim, is:

In an oscillating fan, a base, an oscillating member pivoted on the base, an oscillating table eccentrically pivoted on the member, and a coiled spring having one end attached to the table and the other end attached to a stationary point, the spring being arranged to buckle when its point of attachment to the table aligns with the longitudinal center of the base, whereby the oscillation of the platform is carried past said center. 30 35

In testimony whereof I affix my signature. 40

FRANK M. LANDRUM.
